FENCE POST INSULATOR

Roy C. Ingersoll, Winnetka, Ill., assignor to Borg-Warner Corporation, Chicago, Ill., a corporation of Illinois

Application February 17, 1939, Serial No. 256,964

1 Claim. (Cl. 174—154)

This invention relates to wire insulators and their supports and particularly to an arrangement of this type adaptable to wire fences carrying an electric current. It is the practice in many wire fence installations for confining cattle to impose a small charge of electricity on the wires composing the fence with the result that the cattle become educated to avoid contact with the fence and hence the enormous repair bill normally presented by the usual fence installations is avoided. It is readily appreciated that in this type of installation the problem of providing an efficient yet economical insulation of the wires from the supporting posts is an important and difficult one, and it is to the solution of this problem that the present invention is directed.

It is an object to provide a novel insulator and insulator support for the reception of a horizontally extending wire which will be relatively cheap to manufacture and install and which will effect improved results over the structures heretofore available.

It is a more specific object to provide a special form of opening in a fence post and a special form of semi-flexible insulator for reception in said opening which, when installed, embraces the horizontally extending wire and presents an uninterrupted interior surface for preventing the inadvertent contact of said wire with the post.

A still more detailed object is the provision of a special form of opening in a fence post for the reception of a specially formed insulator including an axially extending slit in the side thereof for the lateral introduction of a horizontally extending wire, the special form of the opening in combination with the special construction of the insulator being effective to maintain the faces of said slit in closely adjacent relation when said insulator is installed in the opening in said post whereby to prevent the inadvertent passage of the wire through said slit into contact with the post.

It is a still further detailed object to provide in the above type of structure a special form of opening in the post for the reception of a specially constructed insulator whereby the turning of the insulator about one quarter turn subsequent to the introduction of the wire is effective to move the faces of the slit in the insulator to either a closely adjacent or actual compressed contact relation for preventing the inadvertent passage of the wire out through the slit into contact with the post.

Other and more detailed objects and advantages of my invention will become apparent from

a reading of the following specification taken in connection with the drawing which forms a part thereof and wherein:

Fig. 1 is a view showing a section of fence incorporating my invention;

Fig. 2 is an enlarged view partly in section substantially on the line 3—3 of Fig. 1 but showing the insulator with the slit therein positioned for reception of a wire;

Fig. 3 is a view similar to Fig. 2 taken on line 3—3 of Fig. 1 showing my improved insulator in its normally installed position wherein it has been turned through substantially a quarter turn from the position shown in Fig. 2 for bringing the faces 10 of the slit therein in closely adjacent relation;

Fig. 4 is a horizontal cross-section taken substantially on the line 4—4 of Fig. 1;

Figs. 5, 6 and 7 show a second modification of insulator and post combination together with one 20 method of installing the same;

Figs. 8 and 9 show an alternative method of introducing the wire into the insulator of the combination shown in Figs. 5 to 7; and

Fig. 10 shows still another modification of my 25 post and wire insulator combination.

Referring in greater detail to the figures of the drawing, I have illustrated by way of example in Fig. 1, a section of a fence embodying my invention and including fence posts 10 having flanges 11 formed with specially constructed openings for the reception of grommets or electrical insulators 12 likewise of a special construction. Electric current conductive fence wires 13 are installed in a special manner within insulators 12 and shown 35 by way of illustration as being supplied with a suitable current of electricity from battery 14 under the control of switch 15. My invention is not directed to nor is it affected by the particular arrangement of current supply employed, the same being equally useful with various forms of circuits. In the first embodiment of my invention illustrated in Figs. 2 through 4, flange 11 of post 10 is formed with a generally elongated or elliptical-like opening 16 therein for the reception and support of insulator 12 in a novel manner that will appear. As illustrated, this elongated or elliptical-like opening is composed of arcuate end portions 17 of a relatively small radius joined by elongated arcuate side portions 18 of increased radius. Communicating with one elongated side portion 18 between the extremities thereof is a slot 19 providing for the lateral introduction of wire 13 in a manner that will appear.

The grommet or electrical insulator 12 of Figs. 2 to 4 is generally tubular in shape and formed

with a centrally extending opening 11 therethrough for the reception of wire 13. This insulator is formed about its periphery with spaced protuberant flanges 22 and 23 which define with the intervening outer periphery 24 of the insulator an annular groove indicated generally at 25. Protuberant flange 23 is formed with an outwardly converging conical face 26 for facilitating the introduction of the insulator into opening 16. The introduction of the insulator into the opening 16 may be readily accomplished by first placing the conical face 26 in contact with opening 16 and applying sufficient coaxial pressure to the insulator to cause its compression and passage of flange 23 through the opening whereupon the insulator again expands to bring the peripheral portion 24 thereof into contact with the wall portions 17 and 18 of opening 16, flange 23 resuming its normal expanded condition and effecting together with flange 22, a locked relation with the surrounding wall of opening 16.

Insulator 12 is further particularly characterized by the fact that it is formed with a slit in the side thereof defined by faces 27 which are positioned in the manner shown in Fig. 2 adaptable for the introduction of wire 13 when the insulator is turned to present the slit defined by the faces 27 adjacent slot 19.

When wire 13 has been inserted in the insulator the same is locked therein in a novel manner against both contact with the sides of opening 16 and against becoming removed through slots 19. This locking is effected by turning insulator 12 through about one quarter turn. By virtue of the elongated shape of opening 16 this turning of insulator 12 causes the same to be compressed and to thus bring faces 27 in close compressed contact relation with each other as indicated in Fig. 3.

Insulator 12 may be made of any well known semi-rigid electrically non-conductive material such, for example, as hard rubber, semi-hard rubber and fabric or semi-hard rubber and steel wire or any well known combination of these materials. I prefer to make the flange 23 somewhat more resilient than the remainder of the insulator, since this facilitates the introduction into the opening 16. The desired relative difference in the resiliency of different portions of the insulator may be obtained by constructing the central portion of the insulator about a steel wire as will be described in connection with subsequent figures.

The above construction of insulator and supporting opening therefor thus provides a number of important advantages. First, there is provided an effective yet relatively inexpensive support and lock between the insulator and the post. Secondly, there is provided a novel structure of insulator and support therefor wherein the wire can be quickly introduced through a slot in the post and a slit in the insulator and subsequently locked in place against either removal from the insulator or electrical contact with the side walls of the opening formed in the post by simply turning the insulator about one quarter turn.

Figs. 5 to 7 illustrate an alternative arrangement differing principally in the fact that a substantially circular insulator and opening therefor is employed and further, in the manner of introduction of the wires. In this modification post 10 is formed with a substantially circular opening 30 in flange 11. Communicating with one side of opening 30 is a slot 31 providing for

the lateral introduction of the wire 13 in a manner to be described.

Insulator 32 is substantially circular in shape formed with central opening 33 for the reception of wire 13 and a slit in the side thereof defined by faces 34 for the introduction of wire 13. The perimeter of the opening 33 in flange 11 is made substantially the same as the perimeter about bottom wall 35 of peripheral groove 36 about insulator 32 whereby to hold faces 34 in compressed relation when the insulator is in place. As a means of adding to the rigidity of the central portions of the insulator relative to the outer part thereof I have indicated a spring steel wire 37. This wire preferably does not extend to the faces 34, since among other things this facilitates the introduction of wire 13 within the insulator.

One method that may be employed in installing the structure of Figs. 5 to 7 comprises first placing the insulator 32 about the wire 13 by first spreading the faces 34 as indicated in Fig. 5 and inserting the wire therein. Following this operation the insulator is next presented with the conical face 38 thereof in contact with the side of opening 30 and sufficient axial pressure applied to the insulator to cause the compression and introduction thereof into the opening 30, with wall 35 in close contact with the wall of the opening and faces 34 of the slit held in closely adjacent or compressed relation as indicated in Fig. 7.

A second method that may be employed in installing the structure disclosed in Figs. 5 to 7 is illustrated in Figs. 8 and 9. In accordance with this technique, the insulator 32 is first positioned within the supporting opening 30 in much the same manner as described in connection with Fig. 6 and including the presentation of conical face 38 into contact with the opening 30 and the application of sufficient coaxial pressure to the insulator to cause its movement into locking relation with the opening. When the wire 13 is to be installed, the faces 34 defining the slit are moved into position opposite the slot 31 in the flange 11 and the wire 13 next placed in contact with the outer edge of the slit. Pressure is applied to the wire to thereby force the wall portions of the insulator adjacent the faces 34 and for some distance therefrom to bend inwardly to thus allow the entrance of the wire 13 into the insulator. This bending of the side wall portions is indicated as taking place generally about points x. When the wire 13 has made its entrance into the insulator, the wall portions adjacent the faces 34 will automatically resume their original positions again bringing the faces 34 into intimate contact with each other. Any subsequent tendency on the part of wire 13 to gain an exit from the insulator in a manner corresponding to its entrance will be without result. This is due to the fact that if force is applied by wire 13 adjacent the inner edge of the faces 34, any bending of the wall portions adjacent said faces must necessarily take place about points y much more closely adjacent the faces than the above referred to points x about which the walls were distorted in providing entry for the wire 13. These second points y are determined by the point of juncture between the side wall defining portions of slot 31 and the side walls of opening 30 and are designated at 39. In other words, the points 39 become the fulcrum points about which the side wall portions of the insulator must be distorted in order to permit of the egress of wire 13 from

the slot 31. It is apparent that with an insulator semi-rigid in character that points 39 will be too closely spaced arcuately with respect to the faces 34 to permit of sufficient distortion of the side wall portions of the insulator to result in the inadvertent passage of wire 13 through the slit defined by faces 34.

It will be seen that this latter technique of installation has certain desirable advantages over the preceding proposed practice, including the fact that the insulators may for example be installed at the factory prior to shipment to eliminate the amount of work that must be done in the field. For example, by following the practice of installing all of the insulators in a line of posts and then following this operation by installing the wire as differentiated from the practice suggested in connection with Figs. 2 and 7 wherein the insulator would be installed in connection with the operation of introducing the wire.

Referring to the modification shown in Fig. 10, I have illustrated a post section 50 that has been perforated in a manner similar to that shown in Fig. 7 to provide an opening referred to generally at 51 wherein the wall portions 52 and 53 have been moved in opposite directions relative to the plane of the post 50 to provide a thread-like opening for the reception of a complementary threaded wire insulator indicated generally at 54. The insulator 54 is formed with a somewhat enlarged head portion 55 and reduced portion 56, a thread 57 being formed about the reduced portion 56 complementary to and arranged for reception in a thread defined by the surrounding wall of the opening 51. A coaxial slot 58 corresponding to that shown in Figs. 5 to 9 is provided for the introduction of a wire to be supported by the insulator 54. The wire to be inserted may be readily introduced either in the manner described in connection with Figs. 5 to 7, or in the manner described in connection with Figs. 8 and 9.

While I prefer to form a supporting opening for the insulator for the above figures directly in a flange in the post itself, it will of course be apparent that in some installations the member in which the opening is formed may as readily be a separate member adapted for attachment to a post.

It will of course be understood that no attempt has been made to follow the actual size of the various elements or their relative sizes to each

other. For example, in actual practice, the wire 13 will be more nearly the same size as the interior of the insulator. This wire can, of course, never actually be as large as the interior of the insulator, since it must pass through the slot 19 in the post and this slot in turn must be considerably less in width than the largest dimensions of the opening 17 or 30, as the case may be, to prevent the inadvertent discharge through the slot of the insulator. These relative sizes will, of course, be determined by the particular installation concerned and I do not wish to be limited by any relative size other than those necessary to make the structure function in the manner above described.

While I have disclosed my invention in connection with certain specific embodiments thereof, I nevertheless contemplate other arrangements as coming within the teaching of my invention and I do not wish to be limited further than as indicated in the appended claim which should be construed as broadly as the prior art will permit.

I claim:

In combination a post and a wire insulator, means on said post defining a supporting opening for the insulator, a slot formed in the side of said means for the lateral introduction of said wire, a tubular semi-flexible wire-receiving electrical insulator formed with a slit in the side wall thereof for the lateral introduction of said wire and formed about the periphery thereof with an annular groove adapted to be forced into embraced relation with said opening defining means in response to the application of a predetermined axial pressure to said insulator, said supporting opening being elongated in shape, said slot in the side of said supporting means being in communication with one of the elongated sides of said supporting opening, said insulator being turnable to a position where said slit therein is juxtaposed with respect to said slot for the lateral introduction of said wire, said elongated shape of said opening being effective in response to the subsequent turning of said insulator about one quarter of a turn to cause the compression of said insulator to bring the faces of said slit in closely adjacent relation to each other whereby to prevent the inadvertent passage of said wire through said slit into contact with the wall of said opening.

ROY C. INGERSOLL.
